FOREIGN PATENT DOCUMENTS

EP 449076 A1 * 10/1991

Primary Examiner — Patricia A Palasik(74) *Attorney, Agent, or Firm* — Studebaker & Brackett
 PC(57) **CLAIM**

The ornamental design for a cable winding machine, as shown and described.

DESCRIPTION

FIG. 1 is a front, top, and left side perspective view of a cable winding machine, showing our new design;
 FIG. 2 is a rear, bottom, and right side perspective view thereof;

FIG. 3 is a front view thereof;
 FIG. 4 is a rear view thereof;
 FIG. 5 is a top view thereof;
 FIG. 6 is a bottom view thereof;
 FIG. 7 is a right side view thereof;
 FIG. 8 is a left side view thereof;
 FIG. 9 is a front view 1 showing the changed state thereof;
 and,
 FIG. 10 is a front view 2 showing the changed state thereof.

1 Claim, 10 Drawing Sheets---
